P. A. BANCEL

AUGMENTER COOLER

Filed Feb. 16, 1921

Patented Sept. 2, 1924.

1,506,805

UNITED STATES PATENT OFFICE.

PAUL A. BANCEL, OF NUTLEY, NEW JERSEY, ASSIGNEE TO INGERSOLL-RAND COMPANY, OF JERSEY CITY, NEW JERSEY, A CORPORATION OF NEW JERSEY.

AUGMENTER COOLER.

Application filed February 16, 1921. Serial No. 445,536.

To all whom it may concern:

Be it known that I, PAUL A. BANCEL, a citizen of the United States, a resident of Nutley, county of Essex, State of New Jersey, have invented a certain Augmenter Cooler, of which the following is a specification accompanied by drawings.

This invention relates to apparatus for devaporizing and cooling a flowing mixture of condensable vapor and gas, as steam and air, but relates more particularly to an augmenter cooler in which the latter part of the total heat abstraction in condensing apparatus takes place.

One object of the invention is to improve upon such condensing apparatus, and secure an augmenter cooler having increased efficiency and requiring a smaller main evacuator, such as a vacuum pump.

In accordance with my construction, the cooler includes a devaporizer and an intercooler, with an augmenter ejector, having one or more jets arranged to discharge into the intercooler, and further objects of the invention are to simplify the apparatus and piping required, cheapen the cost of manufacture, and enable the cooler to be used either with an augmenter ejector or without said ejector device as required, in which case the intercooler becomes part of the devaporizer and adds additional cooling surface to the apparatus.

I prefer to incorporate my augmenter cooler with a surface condenser, preferably by arranging the augmenter cooler against the side of the condenser for convenience, and in order to consume as small space as possible. Such construction also enables me to draw off the condensate between the condenser and the cooler, which is a desirable feature of my construction.

To all of these and other ends, which will hereinafter appear, the invention consists of the apparatus described and claimed in this specification and shown in one of its preferred forms in the accompanying drawings, in which—

Figure 1 is a longitudinal sectional elevation of the augmenter cooler on the line 1—1 of Figure 3 looking in the direction of the arrows, with the casing partly removed and shown partly in outside view,

Figure 2 is an enlarged detail longitudinal sectional view taken through one of the augmenter ejectors,

Figure 3 is a transverse sectional elevation through a condenser and augmenter cooler with the condenser shown in diagrammatic form and partly broken away, and

Figure 4 is a detail longitudinal sectional elevation taken through the discharge outlet of the devaporizer and the inlet of the intercooler, showing a plain cover instead of an augmenter ejector as shown in Figure 1.

Referring to the drawings, the condenser A shown in diagram and broken away in Figure 3, may be of any suitable form and is preferably a surface condenser adapted to be provided with cooling tubes (not shown). The condenser A may be of wedge shaped form, as shown, in which the mixture of condensable vapor and gas, as steam and air, is admitted in the top and after passing downwardly over the condensing surfaces, passes out of the bottom through the outlet B.

The present invention is more particularly concerned with a cooler or that portion of the condensing apparatus in which the latter part of the total heat abstraction takes place. The cooler C, in this instance, in the form of an augmenter cooler, is adapted to be incorporated with the condenser A and is preferably arranged against the lower portion of one side of the condenser, as shown in Figure 3, at an angle to the vertical axis of the condenser. The cooler C is preferably of wedge shaped or pyramidal form, although not necessarily of this form, in which the mixture of air and vapor coming from the condenser after the major portion of steam has been condensed, passes upwardly through the cooler, which is provided with multiple cooling elements or surfaces. A suitable evacuator as a vacuum pump is connected to the cooler, as for instance at the outlet D. The function of the cooler as well understood, is to complete the condensation of the vapor as the mixture flows from the surface condenser, and in accordance with my construction, the cooler includes a devaporizer comprising the chamber E and associated parts, and an intercooler comprising a chamber F forming a part of the cooling apparatus. The devaporizer E and intercooler F are separated by an inclined partition E'.

One or more augmenter ejectors G of the jet type may be arranged to discharge into the intercooler F to increase the absolute pressure of the air in the intercooler.

The cooling apparatus C as a whole, is adapted to be removably secured against the flange H on the side of the condenser A as by means of the bolts J and the space K between the condenser wall and the inner wall or tube sheet L of the cooler forms a water chamber or compartment for the circulation of cooling water through the cooling elements of the cooler. The cooler is provided with an outer head O forming a water circulation compartment P between the head and the outer tube sheet Q of the cooler. The casing of the cooler forms an inlet chamber R at the bottom connecting with the space S at the lower portion of the condenser so that the condensate may be withdrawn through the common outlet T between the condenser and the cooler.

I am not to be understood as limiting the invention to any particular condenser or any particular cooler comprising a devaporizer and an intercooler, but for purposes of illustration, I have shown a devaporizer and intercooler provided with cooling elements in the form of hollow cores or grids U, mounted transversely in rows in the cooler and communicating with the water space K and the water head O of the cooler. These grids may be like those described in my prior Patent No. 1,380,460, granted June 7, 1921, for method and apparatus for devaporizing and cooling. The grids U may be mounted in the tube sheets of the cooler in any suitable manner, as by means of the nipples V, and hand holes W are preferably provided for the cooler opposite each grid. The grids U decrease in number from bottom to top and are preferably closer together in the top rows than in the bottom rows, which decreases the widths of the streams of flowing mixture the greater the relative amount of air in the mixture.

As described in my Patent No. 1,380,460, referred to, interference of the air in the mixture to the process of condensation from a flowing stream can be largely eliminated by the proper disposition of skin resistance in the path of the flow, and I retard the flow of the mixture at points between the relatively cold condensing surfaces X of the grids, but remote from the surfaces themselves. In order to retard the flow of the mixture of steam and air at points between the surfaces X of the grids U, but remote from said surfaces, I have shown transverse fins or flanges Y formed on the grids U and lying in intermeshing relation in planes substantially normal to the core surface X. These fins or flanges Y interpose numerous skin friction surfaces between the cooling surfaces and retard the flow in planes normal to said surfaces. At the condensing surfaces proper, indicated at X, the skin resistance remains the same as before and as though the flanges Y were absent.

The cooling water for the devaporizer and for the intercooler is supplied through the common inlet a to the head O and after passing through the grids, is discharged at the common outlet b from the water space or compartment K. This construction does away with extra piping to and from the intercooler and forms a cheaper and more compact construction than heretofore.

The discharge outlet c of the devaporizer and the inlet d of the intercooler are arranged side by side and a cover seating surface e is formed on the casing common to both the discharge outlet c and the inlet d. The surface e includes the tops of the devaporizer E, the intercooler F, and the partition E' and forms a seat for the removable frame or cover plate f on which is mounted one or more augmenter ejectors G shown in detail in Figure 2, and each comprising the throat g, the steam jet or nozzle j controlled by the valve k and the outlet o controlled by the valve p. In order to shut off one augmenter, both the outlet valve p and the steam nozzle valve k are closed. The frame or cover plate f is removably secured to the cooler as by means of the bolts q and this entire cover plate with the ejector or ejectors may be removed if desired and replaced by a plain cover r indicated in Figure 4.

By placing the augmenter or augmenters G on the cooler, and ejecting from the devaporizer chamber E to the intercooler chamber F, the air from the devaporizer is compressed from absolute pressure to increased absolute pressure in the intercooler. A certain volume of steam is added to the mixture from the augmenter jets j, but most of this steam is removed by condensation in the intercooler thus reducing the cubical contents going to the vacuum pump or other evacuator at the outlet D. The cooling in the intercooler reduces the steam pressure, the total pressure remaining the same and thereby increasing the air pressure and raising the volumetric efficiency on the vacuum pump. Furthermore, by my construction the size of the main evacuator is reduced whether a vacuum pump, second stage steam jet, water jets or other form of evacuator. Because of low first cost, and reduced maintenance, steam jets for evacuation may be cheaply used.

I claim:

1. An augmenter cooler for devaporizing and cooling a flowing mixture of condensable vapor and gas, said cooler being in the form of a unitary structure comprising a wedge shaped casing larger at the bottom and smaller at the top and including a devaporizer and an intercooler, both having multiple cooling elements and connections for the circulation of cooling fluid, an inclined partition separating the devaporizer and in-

tercooler, the devaporizer having an inlet at the bottom for the mixture of vapor and gas, and a discharge outlet at the top, and said intercooler having an inlet at the top 5 adjacent the outlet of the devaporizer and an outlet at the bottom, said devaporizer outlet and intercooler inlet having a common cover seating surface, the outlet of the intercooler being adapted to be connected to evacuating means, and a cover removably mounted on said seating surface and provided with an augmenter ejector operatively connected between the discharge outlet of the devaporizer and the inlet to the intercooler, for increasing 10 the absolute pressure of said mixture.

2. An augmenter cooler for devaporizing and cooling a flowing mixture of condensable vapor and gas, said cooler being in the form of a unitary structure comprising a wedge shaped casing larger at the bottom and smaller at the top and including a devaporizer and an intercooler, both having multiple cooling elements and connections for the circulation of cooling fluid, the cooling elements of the devaporizer being disposed 25

across the path of flow and decreasing in number from bottom to top, an inclined partition separating the devaporizer and intercooler, the devaporizer having an inlet at the bottom for the mixture of vapor and gas and a discharge outlet at the top, and said intercooler having an inlet at the top 30 adjacent the outlet of the devaporizer and an outlet at the bottom, said devaporizer outlet and intercooler inlet having a common 35 cover seating surface, which includes the tops of the devaporizer, the intercooler and the inclined partition, the outlet of the intercooler being adapted to be connected to evacuating means, and a cover removably 40 mounted on said seating surface and provided with an augmenter ejector operatively connected between the discharge outlet of the devaporizer and the inlet to the intercooler, for increasing the absolute pressure 45 of said mixture.

In testimony whereof I have signed this specification.

PAUL A. BANCEL.
